UNITED STATES PATENT OFFICE.

JOSEPH LEIGHTHAM, OF READING, PENNSYLVANIA, ASSIGNOR OF ONE-HALF TO JACOB NOLDE AND JOHN LINDBERG, OF READING, PENNSYLVANIA.

CRANE ATTACHMENT FOR LOADING OR UNLOADING CARS.

SPECIFICATION forming part of Letters Patent No. 775,832, dated November 22, 1904.

Application filed September 2, 1904. Serial No. 223,133. (No model.)

To all whom it may concern:

Be it known that I, JOSEPH LEIGHTHAM, a citizen of the United States, residing in the city of Reading, county of Berks, State of Pennsylvania, have invented certain new and useful Improvements in Crane Attachments for Loading or Unloading Cars, of which the following is a specification.

The object of my invention is to provide a convenient and serviceable hoisting attachment adapted to be readily applied to cars and to serve as a safe and economical means of loading and unloading heavy and unwieldy material, such as railroad-rails.

It is well known that the unloading of heavy rails particularly is not only a difficult and expensive work as ordinarily effected, but that it is attended with considerable risk of injuring the rails in dropping them at desired points and also with considerable danger to those engaged in handling them. To overcome these difficulties and dangers and provide for satisfactorily loading and delivering the rails, as desired, it is essential that a hoisting mechanism be employed; and my invention consists in providing a suitable portable apparatus adapted to be readily applied to and detached from any ordinary gondola-class cars and which is fully described in connection with the accompanying drawings and the novel features pointed out in the claims.

Figure 1 is a side elevation of a crane mechanism embodying my invention, the same being shown attached to a car and suitably anchored. Fig. 2 is a plan view of the same. Fig. 3 is a cross-sectional elevation. Fig. 4 shows a roller-leg employed to facilitate moving of the apparatus upon cars.

A represents an end portion of any ordinary platform or gondola car having inclosing sides *a*, between which railroad-rails or similar heavy freight is carried.

My improved portable hoisting mechanism is adapted to be temporarily attached to a car either for loading or unloading the same and, as shown in the drawings, is constructed as follows: The base portion is made up of two longitudinal channel-beams 10, rigidly con-

nected by an intermediate transverse beam 11, upon which the mast 12 is centrally mounted, 50 and by a parallel transverse beam 13 and diagonal braces 14, connecting the portions which extend rearwardly beyond the end of the car. The longitudinal beams 10 are adapted to rest upon the tops of the inclosing sides *a* of the car, the width of the channels and their spacing apart being such as to permit attachment to cars of varying width without changing and the rearwardly-overhanging portions being anchored by chains 60 15 and rail-engaging bars 15^a, with weighted ends 15^b, or by other suitable means to the road-bed. The mast 12 may be removably mounted upon the intermediate transverse beam 11 and is maintained in upright position by means of a top support 16, adapted to engage the upper extremity thereof, and also by a boom-supporting collar 17, inclosing the same some distance below said top support, and which is rigidly connected to a 65 circular track 18, upon which the overhanging portion of the boom 19 is carried on a roller 20 in swinging around the mast. The track 18 is carried upon opposite posts 21 21 on the longitudinal beams 10 and by a loose 70 ring 22, inclosing the mast 12, above a fixed collar 22^a thereon, said ring being connected by a series of inclined braces 23 to the curved track, and the boom-supporting collar 17 is also connected by transverse bars 24 24 to 80 the upper portions of said post 21 21, while corner-braces 25 and fore-and-aft braces 25^a give rigidity to the structure. A suitable crab mechanism (not shown) is secured to the lower portion of the mast, and tackle 85 connections 26 are provided on the boom to enable the rails or other material operated on to be carried thereby at any desired distance from the end of the car in loading or unloading the same. The top support 16, as 90 shown, comprises a bearing-ring normally engaging the upper end of the mast and connected by diagonal braces 27 27 to the rearwardly-extended longitudinal beams 10 of the base, said bearing-ring being normally held 95 in connection with the top of the mast by a

nut 28 or equivalent means, but being capable of disengagement from the mast, so as to permit the convenient removal or replacement of the boom, which may thus be handled independently, so as to facilitate the application of the hoisting mechanism to successive cars, as required. The structure is very strong relative to the weight, while at the same time readily portable, easily applied, and conveniently operative.

To provide for conveniently moving the mechanism longitudinally from one car to an adjoining one, I preferably employ removable roller-legs, as indicated in Fig. 4, said legs comprising a head-block 30, adapted to fit beneath the longitudinal channel-beams 10 and having terminal flanged rollers 31, adapted to ride upon the sides *a* of the car and upon a bridging-beam extending between adjoining cars.

What I claim is—

1. A crane attachment for cars comprising a base portion made up of parallel beams arranged to rest upon the vertical car sides and an intermediate transverse beam, a mast centrally mounted on said transverse beam, a top support for said mast having diagonal braces attached to the rearwardly-extending portion of said parallel beams, a laterally-braced boom-supporting collar encircling said mast below said top support, a circular track braced to said mast, and a boom rotatable on the latter between said top support and collar and riding upon said track, substantially as set forth.

2. A crane attachment for cars comprising a base portion made up of parallel beams ar-

rangd to rest upon the vertical car sides and an intermediate transverse beam, a mast centrally mounted on said transverse beam, a top support for said mast having diagonal braces attached to the rearwardly-extending portions of said parallel beams and movable into and out of engagement therewith, a laterally-braced boom-supporting collar encircling said mast below said top support, a circular track braced to said mast, and a boom rotatable on the latter between said top support and collar and riding upon said track, substantially as set forth.

3. A crane attachment for cars comprising a base portion made up of parallel beams arranged to rest upon the vertical car sides and an intermediate transverse beam, a mast centrally mounted on said transverse beam, a top support for said mast having diagonal braces attached to the rearwardly-extending portions of said parallel beams and movable into and out of engagement therewith, a laterally-braced boom-supporting collar encircling said mast below said top support, a circular track rigidly connected to said boom-supporting collar and to a bracing-ring carried upon said mast, and a boom rotatable on the latter between said top support and collar and riding upon said track, substantially as set forth.

In testimony whereof I affix my signature in the presence of two witnesses.

JOSEPH LEIGHTHAM.
